WILLIE A. SHIELDS, OF BIRMINGHAM, ALABAMA, ASSIGNOR OF ONE-HALF TO CLIFTON M. ELLIS, OF BIRMINGHAM, ALABAMA.

GARMENT BAGGING MACHINE

Application filed December 18, 1929. Serial No. 414,971.

My invention relates to garment bagging apparatus adapted for use in cleaning and pressing establishments, dry goods stores, etc., and has for its object the provision of an apparatus of the character designated which shall be simple and sturdy of design and reliable and rapid in operation.

A further object of my invention is to provide garment bagging apparatus which shall include a means for supporting a garment to be bagged and power operated means to position a bag for ready placing over the garment.

A still further object of my invention is to provide a garment bagging apparatus including an inclined bag support having means to position a garment to be bagged at the lower end thereof and power operated means for moving a bag upwardly along the inclined support and permitting its gravitational return to position to be placed over the garment.

Garment bagging apparatus as heretofore known to me has usually comprised a vertically extended pole or equivalent means upon which a garment to be bagged is suspended, together with means for engaging and manually raising a bag upwardly on the pole to be released and pulled downwardly over the garment. For example, see my prior Patent No. 1,304,913, issued May 28th, 1919. While such apparatus has proven very successful in use, I have found that by providing an inclined bag support down which a bag may slide by gravity, and by providing power operated means for raising the bag, the rate at which garments may be bagged is greatly increased.

Apparatus embodying features of my invention is illustrated in the accompanying drawings forming a part of this application, in which

Fig. 1 is a view in side elevation of my improved apparatus;

Fig. 2 is a view looking in the direction of the arrows II-II of Fig. 1; and

Fig. 3 is a sectional view taken along the line III-III of Fig. 2.

Referring to the drawings for a better understanding of my invention, my im-

proved apparatus comprises a rectangular frame, only one side of which is shown and which includes front upright supports 10 and rear upright supports 11 with an intermediate upright support 12. Joined to the bottom of the supports 10, 11 and 12 are foundation supports 13 and joined to upper ends of the upright supports 10, 11 and 12 are horizontal frame members 14. The members 10 to 14 inclusive may conveniently be made of standard pipe sections. The apparatus is provided with casters 16 whereby it may be moved from place to place. Suitably mounted in the frame are a plurality of shelves 15 for storing empty bags.

Mounted upon the frame just described at the rear thereof is an upstanding member 17 braced by means of braces 18 and 19 and which is provided on its upper end with a sleeve 21 having a downwardly inclined arm 22. Rigidly secured in the arm 22 is a downwardly inclined pole 23 which extends downwardly to the front of the machine and terminates in a hook 24 adapted to support a garment 26 to be bagged.

Intermediate the front and rear frame members 10 and 11 are upstanding supports 27 and 28 which are secured at their bottoms to the horizontal frame members 14. Pivotally supported at 29 and 31 by the members 27 and 28 is a downwardly inclined platform or slide 32 which is arranged just below the downwardly inclined pole 23. The lower end of the slide 32 rests upon upright supports 33. At the lower end of the slide 32, beneath the pole 23, is provided a trough 34 whereby the lower end of the slide may be raised up level with the lower end of the pole 23. The slide 32 is preferably provided with a relatively large opening 36 across which wires 37 are strung. The purpose of this is to reduce the weight of the slide and to reduce the frictional resistance to sliding.

Mounted in bearings 41 on the transverse member 14, toward the front of the apparatus, are rollers 38 which project upwardly through slots 39 provided in the slide 32 when the slide is in its lower position. The

rollers 38 are driven by a motor 42 suitably supported from the horizontal frame members 14.

The slide 32 is provided with upwardly extending sides 43 which terminate at the lower end in a pair of upwardly extending bearing supports 44. Pivotally mounted in the supports 44 is a rocking frame 46 having downwardly extending arms 47, 48, 49 and 51. Mounted in the lower end of the arms 47 and 48 above one of the slots 39 in the slide 32 and above a driving roller 38, is an idler roller 52. A similar idler roller 53 is mounted in the lower ends of the arms 49 and 51 above the other slot 39 in the slide 32 and above the other driving roller 38. Extending inwardly of the slide 32 and carried by the bearing supports 44 are pins 54 and 56 so positioned that the arms 47 and 51 may be raised above the slide 32 a sufficient distance to clear an empty bag, whereupon the pins engage the arms and any further raising of the arms raises the slide 32 also.

The arms 47 and 51 are each provided with an outwardly extending ear 57 against which rest crank arms 58 and 59 carried by a shaft 61 mounted in the supports 33 beneath the slide 32. The crank arm 59 extends rearwardly of the shaft 61 to form an operating lever 62. Connected to the operating lever 62 is a link 63 which is connected at its lower end to a crank 64. The crank 64 is carried by a shaft 66 mounted in bearings 67 and 68 positioned in the lower portion of the frame. Mounted adjacent the bearing 68 is a plate 69 provided with a recess 71 which is adapted to receive a lug 72 carried by the crank 64. On the inner end of the shaft 66 is a spring 73 which bears against the bearing 68 and a stop 74 so as to urge the crank 64 toward the plate 69. The shaft 66 may be turned by means of a foot pedal 76 on the outer end thereof.

The operation of my improved garment bagging apparatus is as follows:

With the slide 32 and idler rollers 52 and 53 in the position shown in the drawing, and the motor 42 running, an empty bag is threaded over the pole 23 and passed between the idler and driving rollers whereupon it is forced upwardly in the slide 32. While the bag is moving to its upper position a garment 26 is hung on the hook 24 at the lower end of the pole 23. The pedal 76 is then operated to raise the idler rollers 52 and 53 off the bag and to raise the slide 32 up level with the inclined pole 23. In this position the lug 72 falls into the recess 71 to hold the rollers and the slide in their upper positions. The slide is then above the driving rollers 38 to permit free return of the empty bag. When the idler rollers and slide are thus raised, the bag returns by gravity down the pole 23 and is pulled by

hand down over the garment 26. The pedal 76 is then operated to permit the idler rollers and slide to lower whereupon the apparatus is ready to repeat the operation described.

From the foregoing it will be apparent that I have devised an improved garment bagging apparatus which is simple of construction and operation and which embodies power operated means for raising the bags to a position to be pulled down over the garments to be bagged. This provision of power operated means frees the hands of the worker to position a garment for bagging and accordingly practically doubles the rate at which garments may be bagged as compared with wholly manually operated means.

While I have shown my invention in but one form, it will be obvious to those skilled in the art that it is not so limited but is susceptible of various changes and modifications without departing from the spirit thereof, and I desire therefore that only such limitations shall be placed thereupon as are imposed by the prior art, or as are specifically set forth in the appended claims.

What I claim is:

1. In a garment bagging machine, a fixedly secured pole for slidably supporting an empty bag and disposed at an angle to the horizontal, means for mounting a garment to be bagged at the lower end thereof, a slide extending in substantial parallelism with the pole positioned below the pole for supporting the sides of the bag, said slide being pivotally mounted below the pole, and means for raising the lower end of the slide up level with the pole.

2. In a garment bagging machine, a fixedly secured pole for slidably supporting an empty bag and disposed at an angle to the horizontal, means for mounting a garment to be bagged at the lower end thereof, a slide extending in substantial parallelism with the pole positioned below the pole for supporting the sides of the bag, and mechanical means for moving a bag upwardly along the pole and slide.

3. In a garment bagging machine, a fixedly secured pole for slidably supporting an empty bag and disposed at an angle to the horizontal, means for mounting a garment to be bagged at the lower end thereof, a slide extending in substantial parallelism with the pole positioned below the pole for supporting the sides of the bag, and roller means for moving a bag upwardly along the pole and slide.

4. In a garment bagging machine, a fixedly secured pole for slidably supporting an empty bag and disposed at an angle to the horizontal, means for mounting a garment to be bagged at the lower end thereof, a slide extending in substantial parallelism with the pole positioned below the pole for

supporting the sides of the bag, said slide being pivotally mounted below the pole, means for raising the lower end of the slide into the inclined plane of the pole, and 5 power driven roller means for moving a bag upwardly along the pole and slide.

5. In a garment bagging machine, a fixed-
ly secured pole for slidably supporting an
empty bag and disposed at an angle to the
horizontal, means for mounting a garment
to be bagged at the lower end thereof, a
slide extending in substantial parallelism
with the pole positioned below the pole for
supporting the sides of the bag, said slide
15 being pivotally mounted below the pole,
means for raising the lower end of the slide
into the inclined plane of the pole, power
driven roller means for moving a bag up-
wardly along the pole and slide, and means
20 for disengaging the power driven means to
permit gravitational return of the bag along the
pole and slide.

6. In a garment bagging machine, a fixed-
ly secured pole for slidably supporting an
empty bag and disposed at an angle to the
horizontal, means for mounting a garment
to be bagged at the lower end thereof, a
slide extending in substantial parallelism
with the pole positioned below the pole for
25 supporting the sides of the bag, said slide
being pivotally mounted below the pole,
means for raising the lower end of the slide
into the inclined plane of the pole, power
driven driving rollers for elevating a bag,
30 said rollers being mounted below the slide
and projecting therethrough, and idler rollers
mounted above the slide and adapted
to cooperate with the driving rollers.

7. In a garment bagging machine, a fixed-
ly secured pole for slidably supporting an
empty bag and disposed at an angle to the
horizontal, means for mounting a garment
to be bagged at the lower end thereof, a slide
extending in substantial parallelism with the
45 pole positioned below the pole for support-
ing the sides of the bag, said slide being piv-
otally mounted below the pole, means for
raising the lower end of the slide into the
inclined plane of the pole, power driven
50 driving rollers for elevating a bag, said
rollers being mounted below the slide and
projecting therethrough, idler rollers mount-
ed above the slide and adapted to cooperate
with the driving rollers, and means for mov-
55 ing the idler rollers out of engagement with
the driving rollers.

8. In a garment bagging machine, a fixed-
ly secured pole for slidably supporting an
empty bag and disposed at an angle to the
60 horizontal, means for mounting a garment
to be bagged at the lower end thereof, a slide
extending in substantial parallelism with the
pole positioned below the pole for support-
ing the sides of the bag, said slide being
65 pivotally mounted below the pole, means for

raising the lower end of the slide into the
inclined plane of the pole, power driven
driving rollers for elevating a bag, said
rollers being mounted below the slide and
projecting therethrough, idler rollers mount-
70 ed above the slide and adapted to cooperate
with the driving rollers, and means for mov-
ing the slide above the horizontal plane of
the driving rollers.

9. In a garment bagging machine, a fixed-
ly secured pole for slidably supporting an
empty bag and disposed at an angle to the
horizontal, means for mounting a garment
to be bagged at the lower end thereof, a
slide extending in substantial parallelism
80 with the pole positioned below the pole for
supporting the sides of the bag, said slide
being pivotally mounted below the pole,
means for raising the lower end of the slide
into the inclined plane of the pole, power
85 driven driving rollers for elevating a bag,
said rollers being mounted below the slide
and projecting therethrough, idler rollers
mounted above the slide and adapted to
cooperate with the driving rollers, means for
90 moving the slide above the horizontal plane
of the driving rollers, and means adapted to
sustain the idler rollers and the slide in a
raised position until released.

In testimony whereof I affix my signature. 95
